UNITED STATES PATENT OFFICE.

WILLIAM WILSON, OF BOSTON, MASSACHUSETTS, ASSIGNOR TO
CAMPBELL-BOSWORTH MACHINERY COMPANY, OF PORT-
LAND, MAINE, A CORPORATION OF MAINE.

SEWING-MACHINE.

No. 834,436.

Specification of Letters Patent.

Patented Oct. 30, 1906.

Application filed October 21, 1905. Serial No. 283,753.

To all whom it may concern:

Be it known that I, WILLIAM WILSON, a citizen of the United States, residing at Boston, in the county of Suffolk and State of Massachusetts, have invented certain new and useful Improvements in Sewing-Machines; and I do hereby declare the following to be a full, clear, and exact description of the invention, such as will enable others skilled in the art to which it appertains to make and use the same.

The present invention relates to straight needle leather-sewing machines provided, in addition to the usual sewing instrumentalities, with a tool or tools secured to and actuated by the needle-bar or the awl-bar for operating upon the work adjacent to the needle or awl; and the object of the invention is to improve the means by which such tools are mounted upon and secured to the needle-bar or the awl-bar with respect to facility of adjustment and security and in other respects hereinafter pointed out.

The invention consists in a sewing-machine embodying substantially the construction hereinafter described, and illustrated in the accompanying drawings, in which—

Figure 1 shows in elevation a portion of a sewing-machine including the needle-bar provided with a needle and a grooving-tool. Fig. 2 is an elevation of the needle-bar, needle, and grooving-tool. Fig. 3 is a vertical section of the grooving-tool. Fig. 4 is a vertical section of the clamping-sleeve. Fig. 5 is a vertical section of the upper part of the needle-bar, and Fig. 6 is an elevation of the grooving-tool as seen from right to left in Fig. 2.

The invention, as shown in the drawings, is embodied in a grooving-tool secured to the needle-bar; but it is equally adapted for use in connection with other tools for operating adjacent to the needle or awl, such as stitch separating or finishing tools, and the tool may be secured to the awl-bar instead of the needle-bar. The sewing-machine as a whole is not shown, as it may be of any usual or suitable form.

In the illustrated embodiment of the invention the needle-bar 1 slides in a recess 2 in the frame 3 of the machine and carries a hooked needle 4 and a grooving-tool 5. The

grooving-tool is of the form shown, and is adapted to operate in the manner described in the patent to Wheeler, No. 446,398. The 55 needle-bar is provided with a reduced extremity and a socket 6, in which the shank of the needle is held by jaws 7, formed by tapering and splitting the end of the needle-bar. The grooving-tool 5 has a shank 8 centrally perforated for the reception of the needle and provided with a tapered recess 9, which engages the tapered jaws 7. A clamping-sleeve 10 is provided with right and left hand threads which engage corresponding 65 threads on the needle-bar 1 and the shank 8 of the grooving-tool, and the upper end of the sleeve 10 is squared for the convenient application of a wrench in turning it. When the parts are in place, a partial turn of the sleeve 70 10 draws the shank 8 tightly against the jaws 7, thereby forcing the jaws against the needle-shank and simultaneously securing the needle and the grooving-tool. Upon unscrewing the sleeve 10 slightly the needle 75 may be removed or adjusted, and the tool 5 may be turned to adjust its position or may be entirely unscrewed and replaced with another.

An important feature of the invention consists in the fact that the diameter of the sleeve 10 may be made equal to that of the needle-bar, so as to form a continuation thereof and permit the upper extremity of the device to be drawn down into the recess 2, in 85 which the needle-bar slides, as is necessary in the well-known Campbell straight-needle machine, there being no lateral projection to prevent this. The shank of the grooving-tool is of ample dimensions to resist the 90 thrust of the tool against the work, and it is securely fixed in place, being tightly engaged both by the clamping-sleeve and by the tapered extremity of the needle-bar. A single 95 operation serves to secure or loosen both the needle and the tool, and either of these may be turned to the desired position independently of the other.

Where in the claims the terms "needle" and "needle-bar" are used, these terms are not intended to preclude the definition of the invention as applied to the awl and awl-bar, to which the invention may in some instances be applied.

Having now described the invention, what is claimed is—

1. The combination, in a sewing-machine, of a needle, a needle-bar carrying the needle having a screw-threaded portion on its needle-holding end, a tool for operating on the work adjacent to the needle having a screw-threaded portion and a sleeve having two screw-threaded portions engaging the screw-threaded portions of the needle-bar and tool respectively and securing the tool on the needle-bar, substantially as described.

2. The combination, in a sewing-machine, of a needle-bar, a needle, and a tool for operating upon the work adjacent to the needle, and means for securing the needle and the tool simultaneously on the needle-bar comprising a rotatable sleeve forming a continua-

tion of the needle-bar, substantially as described.

3. The combination, in a sewing-machine, of a needle-bar, provided with screw-threads and with tapered needle-clamping jaws, a tool having a screw-threaded shank with a tapered recess, and a screw-threaded sleeve for engaging and drawing together the tool-shank and the needle-bar so as to secure simultaneously the needle and the tool, substantially as described.

In testimony whereof I affix my signature in presence of two witnesses.

WILLIAM WILSON.
